UNITED STATES PATENT OFFICE.

GEORGE BURKHART, OF NATIONAL MILITARY HOME, OHIO.

WINDOW-SASH.

SPECIFICATION forming part of Letters Patent No. 792,814, dated June 20, 1905.

Application filed April 3, 1905. Serial No. 253,578.

To all whom it may concern:

Be it known that I, GEORGE BURKHART, a citizen of the United States, residing at National Military Home, in the county of Montgomery and State of Ohio, have invented certain new and useful Improvements in Window-Sashes, of which the following is a specification.

My invention relates to improvements in window-sashes; and it consists in the constructions, combinations, and arrangements herein described and claimed.

The objects of my invention are to provide a simple means for conveniently inserting window lights or panes in the sashes and securing them weather-tight in position.

Referring to the accompanying drawings, forming a part of this application, and in which similar reference-numerals indicate corresponding parts in both views, Figure 1 is a front elevation of a twelve-light window-sash, illustrating one embodiment of my invention. Fig. 2 is a sectional view on the line 2-2 of Fig. 1.

Referring especially to Figs. 1 and 2, 1, 2, 3, and 4 indicate, respectively, the top, bottom, and side rails of a window-sash provided with three vertical division-bars 5, 6, and 7 and two horizontal division-bars 8 and 9. As shown especially in Fig. 2, the bar 8 is provided with slots 10, extending across and communicating with tapered recesses or grooves 11 and 12, formed in the coöperating faces of the side rails and vertical bars. The tapered grooves are formed with their inner face 13 parallel with the plane of the window-sash and with their outer face 14 inclined from the outer edge of the communicating slots 10, the portions of said grooves adjacent the slot 10 being formed of greater width than that of said slot in order to provide shoulders 15 for furnishing a secure weather-tight seat for the edges of the window-lights when clamped in place. A screw 16 extends through each of the slots 10 for securing a clamping-washer 17 against the adjacent portions of the two lights inserted in the grooves 11 and 12, thereby providing a simple means for securely

clamping said lights against the faces 13 of said slots. It will be seen that my invention provides a common clamping means for two adjacent lights which is simple and efficient in construction.

The lower bar 9 is provided with slots 18, extending across and communicating with the tapered recesses or grooves 19, formed in the coöperating faces of the side rails and vertical bars, the construction being similar to that just described in relation to the slots 10 and tapered grooves 12. A screw 20 extends through each of the slots 18 in position to engage the upper portion of a light 21 for securely clamping it in the grooves 19.

From the above description it will be seen that my invention provides a reliable means for conveniently securing window-lights in sashes provided with any number of lights.

Having thus described my invention, what I claim as new, and desire to secure by Letters Patent, is—

1. In a window-sash, the combination of the usual top, bottom and side rails, horizontal bars provided with slots, and vertical bars, said vertical bars and side rails constructed with tapering grooves extending in both directions from said slots, substantially as described.

2. In a window-sash, the combination of the usual top, bottom and side rails, horizontal bars provided with slots, vertical bars, said vertical bars and side rails constructed with tapering grooves extending in both directions from said slots, and a common clamping means for clamping the two lights inserted in the grooves extending from each slot, substantially as described.

3. In a window-sash, the combination of the usual top, bottom and side rails, horizontal bars provided with slots, vertical bars, said vertical bars and side rails constructed with grooves extending in both directions from said slots, and a common clamping means in each of said slots for clamping the two lights inserted in the grooves extending therefrom, substantially as described.

4. In a window-sash, the combination of the

usual top, bottom and side rails, horizontal bars provided with slots, and vertical bars, said vertical bars and side rails constructed with tapering grooves extending from said 5 slots, and securing devices extending into said tapering grooves adjacent said slots, substantially as described.

In testimony whereof I affix my signature in presence of two witnesses.

GEORGE BURKHART.
